UNITED STATES PATENT OFFICE.

BALDWIN H. KANNENBERG, OF RIVER FOREST, ILLINOIS, ASSIGNOR TO AMERICAN CAN COMPANY, OF NEW YORK, N. Y., A CORPORATION OF NEW JERSEY.

DELIVERY MECHANISM.

1,264,527.

Specification of Letters Patent. Patented Apr. 30, 1918.

Application filed August 7, 1915. Serial No. 44,164.

To all whom it may concern:

Be it known that I, BALDWIN H. KANNENBERG, a citizen of the United States, residing in River Forest, in the county of Cook and State of Illinois, have invented a new and useful Improvement in Delivery Mechanisms, of which the following is a specification.

This invention relates in general to delivery or receiving mechanisms and more particularly to receiving mechanisms adapted to continuously receive blanks and other articles from a continuously operating machine or apparatus. It is hereinafter described in connection with a press for die cutting metal blanks, although it will be manifest that it may, with slight and obvious adaptations, be utilized effectively in connection with machines of widely differing characteristics.

A principal object of this invention is the provision of a mechanism or device for receiving blanks or articles from a die or punch press and the like without interference with the operation of said die or punch press when it is desired to remove articles from said delivery mechanism.

A further object of the invention is the provision of a device or mechanism which will receive blanks or the like stacked and ready for removal, said stack of blanks or articles being disposed when desired out of the way of subsequently entering blanks or articles and in convenient position to be removed.

A further object of the invention is the provision of a mechanism or device of the character described which may be used with a die or punch press producing a plurality of blanks at a single operation, all of the articles resulting from successive operations being nicely piled.

A further object of the invention is the provision of such a mechanism or device wherein the scrap occasioned by the cutting or punching of the stock or the forming of the article or blank, will be delivered out of the machine and in such fashion as to not interfere with the handling of the blanks and articles themselves.

A further object of the invention is the provision of such a mechanism that may be

manually operated with the expenditure of little effort.

A still further object of the invention is the provision of such a mechanism or device of simple and economical construction and consisting of few and simple parts constructed and arranged to provide a delivery or receiving mechanism of durable character and which will not need frequent or material repair.

Other objects and advantages of the invention will be apparent as it is better understood from the following description when considered in connection with the accompanying drawing illustrating a preferred embodiment thereof.

Referring to the drawings:

Figure 1 is a front elevation of a punch press provided with a delivery or receiving mechanism embodying my invention;

Fig. 2 is a longitudinal section taken vertically through the same; and

Fig. 3 is an enlarged detail sectional view showing certain features of construction.

For the purpose of illustrating my invention I have shown on the drawings a machine adapted for the cutting of strips which form blanks from which can heads or other articles may be cut. In this machine a suitable base 4 carries at its top and rear a table 5 over which metal plate may be fed in any approved manner. The base 4 forms a bearing for a shaft 6 carrying a suitable pulley 7, a crank disk and pin 8 which drives a vertically reciprocating die carrying head or punch 9 in standards 10 extending above the level of the table 5. In the present instance this die is adapted to cut at its forward edge 11 and at its rear edge 12. The metal sheet shown at 13 is intended to provide five blanks at three cuttings of the die; the first cutting takes off the front edge 14 of the strip, the second cutting produces two blanks 15 and 16, the blank 15 being formed of the material wholly in front of the die as it cuts, and the blank 16 by the material defined by the edges 11 and 12 in cutting. At the third operation three blanks are formed, the forward one 17 of the material in front of the die in cutting, the central one 18 of the material disposed directly beneath the die, and the rear one 19 of the material disposed be-

hind the die at its last or third cutting operation. It will be understood that the number of blanks or rows of blanks to be obtained from a single sheet may be increased 5 by increasing the length of the sheet or by using a smaller or narrower die. The press shown on the drawing, however, will deliver no blank at its first cut if an edge is to be cut off. It will deliver two blanks 10 at each cutting after the first and until the last cutting, when it will deliver three. If no front edge is to be cut off, the first cutting operation of the die will cut two blanks and each succeeding operation will cut two 15 until the last, which will cut three.

Guide-ways 21, 22, 23 and 24 are provided. The guide-way 21 delivers the scrap or the edge cut off outside of the machine and outside of the receiver, and without interfering 20 with the delivery or receiving mechanism. This guide is positioned to take scrap or scrap edges as they fall beneath the die itself and its upper and rear end 25 is disposed sufficiently far to the rear to permit the scrap to 25 be received. From this end it extends downwardly and forwardly to its lower end 26, over which the scrap falls into a suitable box 27 or upon the floor. The guide-ways 22, 23 and 24 deliver respectively the blanks cut 30 from in front of the die, the blanks cut beneath the die and the blanks left behind the die after the cutting operation. The blanks are delivered by these guide-ways to a receiver, which comprises a shelf or receptacle 35 28, 29 and 31 for each guide-way and carried in a framework 32. In the present instance this framework is equal to a length and half length of the shelf, so that the shelves mounted in it occupy two-thirds of its length. It 40 consists of uprights 33 having three pairs 34 of horizontally disposed tracks extending across the machine, and the shelves are mounted upon suitable rollers or other anti-friction device 35 so that they are laterally 45 movable across the machine on the tracks. The shelves are connected at each end to a pair of uprights 36, one located at each end of the shelves and secured to all three of them so that movement of one shelf is accom- 50 panied by movement of the others, the upper end of the rods 36 serving as handles for moving the receiving shelves. The shelves are each of length more than twice the length of blanks received by them, so 55 that one end of the shelf may be disposed at the receiving station in front of the guide-ways 22, 23 and 24 and the other at a side of the machine.

In use the blanks from in front of the 60 punch slide down the guide 22 and onto the uppermost receiving shelf 28, a suitable apron 37 being provided if desired to accurately place them on the shelf. The blanks falling from beneath the die drop upon the 65 guide 23 and are delivered to the inter-

mediate shelf, which may have an apron 38 fastened to it if desired. The upper end of this guide is spaced well away from beneath the cutting edge 12 in order that the strips or scrap 39 may fall behind it onto the guide 21, but it extends sufficiently toward the rear to insure the blanks cut beneath the die falling accurately down upon it. The blanks formed from behind the die fall onto the guide-way 24 and are delivered to 70 the lowermost shelf, which may have an apron 41 like the apron 38 or like the apron 37. The aprons 41 and 38 in the present instance are fastened to the movable shelves and the apron 37 to the track upon which its 80 shelves move. The blanks are allowed to accumulate upon various shelves until the halves of the shelves in receiving position are nearly filled. A handle 36 is then grasped and the shelves moved to the other end of 85 their lateral travel, bringing half of the shelves which have just received the blanks out of receiving position and bringing the other half of the shelves into receiving position. The blanks accumulated may be lifted 90 out without disturbing the continuous action of the machine and the shelves reciprocated in the opposite direction when the halves of the shelves in receiving position have received a charge to be removed. The structure 95 consists of few and simple parts, readily operated by hand and of durable construction and arrangement.

It is thought that the invention and many of its attendant advantages will be understood from the foregoing description, and it will be apparent that various changes may be made in the form, construction and arrangement of the parts without departing from the spirit and scope of the invention 100 or sacrificing any of its material advantages, the form hereinbefore described being merely a preferred embodiment thereof.

I claim:

1. In a machine of the character described, the combination of means for dividing an article, delivery devices for the parts thereof, receivers for the parts thereof, said receivers being connected end to end in pairs and being transversely shiftable together 115 relative to said delivery devices to bring either receiver across the line of delivery of said parts, and a support for said receivers.

2. In a machine of the character described, the combination of means for dividing an 120 article, delivery devices one above the other for the divided parts, receivers for the said parts, said receivers being arranged one above the other and connected with each other and being transversely shiftable together to bring both receivers across the lines of delivery of said parts, and a support for said receivers.

3. In a machine of the character described, the combination of a machine for operating 130

upon an article, and a receiver laterally shiftable through a fixed path of travel, said receiver normally having one-half of it disposed in receiving position and the other half in position to permit removal of the articles previously received, said receiver having movement laterally of said machine and transversely to the direction of movement of said articles to alternately bring its halves into receiving position.

4. In a machine of the character described, the combination of means for dividing an article, delivery devices for the parts thereof, receivers for the said parts, said receivers being connected end to end in pairs and a plurality of said pairs being arranged and connected one pair above another, and said receivers being transversely shiftable together to bring a plurality of receivers across the lines of delivery of said parts.

5. In a machine of the character described, the combination of means for dividing an article, delivery devices for the parts thereof, receivers for the said parts, said receivers being connected end to end in pairs and a plurality of said pairs being arranged and connected one pair above another, and said receivers being transversely shiftable together to bring a plurality of receivers across the lines of delivery of said parts.

6. In a machine of the character described, the combination of means for dividing an article, delivery devices for the parts thereof, receivers for the said parts, said receivers being connected end to end in pairs and a plurality of said pairs being arranged one pair above another, and a unitary carriage for said receivers whereby they are shiftable together to bring a plurality of receivers across the lines of delivery of said parts.

7. In a machine of the character described, the combination of a machine from which a plurality of articles are simultaneously delivered, and a receiver for said articles, said receiver having receiving parts corresponding in number to the number of deliveries at an operation of said machine, all of said parts being shiftable together laterally of the machine and transversely to the direction of movement of said articles to permit removal of said articles without interrupting the action of said machine, and means for delivering scrap out of said machine and receiver.

8. The combination of a die punch adapted to cut a plurality of blanks at a single operation, a guide-way for each blank produced at a single operation, and a receiver for receiving said blanks from said guide-ways, said receiver comprising a shiftable frame movable transversely to the direction of advance of said blanks, tracks on which said frame is movable, a plurality of shelves carried by said frame for receiving articles from said guide-ways, said shelves being ar-

ranged side by side in pairs and a plurality of such pairs being arranged one above another corresponding with the blank-deliveries of the machine, said frame being of sufficient length to permit an end of it to extend out of receiving position when the other end is in receiving position.

9. The combination of cutting means adapted to sever a sheet into a plurality of parts; receptacles for the said sheet-parts; and guideways leading to said receptacles respectively, the upper ends of said guideways being arranged substantially under a line of cutting of said cutting means, and at a point to the front of said line, respectively, to receive and guide the sheet-parts which are separated from the said sheet by the cutting means and are thereby left at different locations, said receptacles being arranged and connected in pairs end to end and laterally shiftable together.

10. The combination of cutting means adapted to sever a sheet into a plurality of parts; receptacles for the said sheet-parts; and guide-ways leading to said receptacles respectively, the upper ends of said guideways being arranged substantially under a line of cutting of said cutting means, and at a point to the front of said line, and at a point to the rear of said line, respectively, to receive and guide the sheet-parts which are separated from the said sheet by the cutting means and are thereby left at different locations, said receptacles being arranged and connected in pairs end to end and there being a plurality of connected pairs one above another, and said receptacles being laterally shiftable together.

11. The combination of cutting means adapted to sever a sheet into a plurality of parts; receptacles for the said sheet-parts, said receptacles having rear aprons; and guideways leading to said receptacles respectively, the upper ends of said guideways being arranged substantially under a line of cutting of said cutting means, and at a point to the front of said line, respectively, to receive and guide the sheet-parts which are separated from the said sheet by the cutting means and are thereby left in different locations, said receptacles being arranged and connected in pairs end to end and laterally shiftable together.

12. The combination of cutting means adapted to sever a sheet into a plurality of parts; receptacles for the said sheet-parts located at an end of the machine below the plane of the cutting operation and spaced apart one above another; and guideways leading downward and longitudinally to said receptacles respectively, the upper ends of said guideways being arranged substantially under a line of cutting of said cutting means, and at a point to the front of said line, respectively, to receive and guide the

sheet-parts which are separated from the said sheet by the cutting means and are thereby left at different locations, said receptacles being arranged and connected in pairs 5 end to end and laterally shiftable together.

13. The combination of cutting means adapted to sever a sheet into a plurality of parts; shiftable receptacles for the said sheet-parts located at an end of the machine 10 below the plane of the cutting operation and spaced apart one above another, the said receptacles being connected and shiftable together; and guideways leading downward and longitudinally to said receptacles respectively, the upper ends of said guideways being arranged substantially under a line of cutting of said cutting means, and at a point to the front of said line, respectively, to receive and guide the sheet-parts which 15 are separated from the said sheet by the cutting means and are thereby left at different locations.

14. The combination of cutting means adapted to sever a sheet into a plurality of parts; shiftable receptacles for the said sheet-parts located at an end of the machine below the plane of the cutting operation and spaced apart one above another; guideways leading downward and longitudinally 20 to said receptacles respectively, the upper ends of said guideways being arranged substantially under a line of cutting of said cutting means, and at a point to the front of said line, respectively, to receive and guide the sheet-parts which are separated from the said sheet by the cutting means and are thereby left at different locations; and means 25 for guiding said receptacles as they are shifted, said receptacles being arranged and connected in pairs end to end and laterally shiftable together.

15. The combination of cutting means adapted to sever a sheet into a plurality of parts; sets of duplicate shiftable receptacles 30 for the said sheet-parts located at an end of the machine below the plane of the cutting operation and spaced apart one above another; guideways leading downward and longitudinally to said receptacles respectively, the upper ends of said guideways being arranged substantially under a line of cutting of said cutting means, and at a point to the front of said line, respectively, to receive and guide the sheet-parts which are 35 separated from the said sheet by the cutting means and are thereby left at different locations; and means for guiding said receptacles as they are shifted.

16. The combination of cutting means 40 adapted to sever a sheet into a plurality of separate parts, said sheet-parts being thereby left at different locations nearer to or farther from the end of the machine; receptacles for the said parts; a guideway leading 45 from near the rear of the said cutting means

to one of said receptacles; a guideway leading from near the front of said cutting means to another of said receptacles; and a guideway leading from a point farther in front of said cutting means to another of 70 said receptacles, said guideways being adapted to severally receive the differently located severed sheet parts, said receptacles being arranged and connected in pairs end to end and laterally shiftable together. 75

17. The combination of cutting means adapted to sever a sheet into a plurality of separate parts, said sheet-parts being thereby left at different locations nearer to or farther from the end of the machine; receptacles for the said parts arranged at an end of the machine and spaced apart one above another; a guideway leading from near the rear of the said cutting means to an upper one of said receptacles; a guideway leading 80 from near the front of said cutting means to the next lower of said receptacles; and a guideway leading from a point farther in front of said cutting means to the next lower of said receptacles, said guideways being 85 adapted to severally receive the differently located severed sheet parts, said receptacles being arranged and connected in pairs end to end and laterally shiftable together.

18. The combination of cutting means 90 adapted to sever a sheet into a plurality of separate parts, said sheet-parts being thereby left at different locations nearer to or farther from the end of the machine; shiftable receptacles for the said parts arranged 95 at an end of the machine and spaced apart one above another; a guideway leading from near the rear of the said cutting means to one of said receptacles; a guideway leading 100 from near the front of said cutting means to another of said receptacles; a guideway leading from a point farther in front of said cutting means to 105 another of said receptacles; a guideway leading from a point farther in front of said cutting means to another of said receptacles, said guideways being adapted to severally receive the differently located severed sheet 110 parts; and means for guiding and shifting said receptacles transversely of the machine, said receptacles being arranged and connected in pairs end to end and laterally shiftable together. 115

19. The combination of cutting means adapted to sever a sheet into a plurality of separate parts, said sheet-parts being thereby left at different locations nearer to or farther from the end of the machine; shiftable receptacles for the said parts arranged 120 at an end of the machine and spaced apart one above another; a guideway leading from near the rear of the said cutting means to an upper one of said receptacles; a guideway leading 125 from near the front of said cutting means to the next lower of said receptacles; a guideway leading from a point farther in front of said cutting means to the next lower of said receptacles, said guideways being 130

adapted to severally receive the differently located severed sheet parts; and means for guiding and shifting said receptacles transversely of the machine, said receptacles being arranged and connected in pairs end to end and laterally shiftable together.

20. The combination of cutting means adapted to sever a sheet into a plurality of separate parts, said sheet-parts being there-
10 by left at different locations nearer to or farther from the end of the machine; shift-
able receptacles for the said parts arranged at an end of the machine and spaced apart one above another and connected and mov-
15 able together; a guideway leading from near the rear of the said cutting means to one of said receptacles; a guideway leading from near the front of said cutting means to another of said receptacles; a guideway lead-
20 ing from a point farther in front of said cutting means to another of said receptacles, said guideways being adapted to severally receive the differently located severed sheet parts; and means for guiding and shifting
25 said receptacles transversely of the machine,

said receptacles being arranged and connected in pairs end to end and laterally shiftable together.

21. The combination of cutting means having spaced-apart front and rear cutting 30 edges adapted to sever a sheet into a plural-
ity of parts; receptacles for said sheet-parts; a guideway arranged to receive the severed sheet-part from the rear of said cutting means; a guideway arranged to receive the 35 severed sheet-part from between said cutting edges; and a guideway arranged to receive the severed sheet-part from the front of said cutting means; said guideways leading re-
spectively to said receptacles, said recepta- 40 cles being arranged and connected in pairs end to end and laterally shiftable together.

In testimony whereof, I have hereunto set my hand in the presence of two subscribing witnesses.
